Primary Examiner — Jennifer L Watkins*Assistant Examiner* — Samantha Lynne Brodowski(74) Attorney, Agent, or Firm — Dunlap Bennett & Ludwig, PLLC; Brendan E. Squire(57) CLAIM

The ornamental design for a handbag, as shown and described.

DESCRIPTION

FIG. 1 is a perspective view of the handbag showing my new design;

FIG. 2 is a right side elevation view thereof;

FIG. 3 is a left side elevation thereof;

FIG. 4 is a front elevation view thereof;

FIG. 5 is a rear elevation view thereof;

FIG. 6 is a top plan view thereof; and,

FIG. 7 is a bottom plan view thereof.

The broken lines shown in the drawings illustrate portions of the handbag that form no part of the claimed design.

The stippling in the drawings depict a contrasting material.
